CALENDER ROLL GUIDE AND FEED MECHANISM

Walter W. Neely, Alton, Ill., assignor of one-half to Herbert W. McAfoos, Alton, Ill.

Application September 24, 1947, Serial No. 775,922

4 Claims. (Cl. 92—74)

1

This invention relates to paper calendering machines and in its more specific aspects is directed to a paper strip feeding or guide means for the calendering machine.

The object of the invention is to provide a series of feed or guide mechanisms for calendering machines which will enable the paper stock to be threaded through the machine without manual attention after being manually threaded into the first pass in the calendering machine.

In the drawings:

Fig. 1 is a front elevational view of a calendering machine incorporating the invention;

Fig. 2 is a sectional view taken substantially along the line 2—2 of Fig. 1;

Fig. 3 is a view taken along the line 3—3 of Fig. 2 to illustrate the feed and guide mechanism compression adjusting means;

Fig. 4 is a view similar to Fig. 3 but with the feed and guide mechanism compression adjusting mechanism in a different position of adjustment; and

Fig. 5 is an enlarged sectional view of two of the rolls shown in Fig. 2 and associated feed and guide mechanism.

Referring now to the drawings, numerals 1 and 2 designate the upright members and 3 and 4 designate the base and top members, respectively, of a calendering roll stand frame. A series of calendering rollers 5, 6, 7, 8, and 9 are rotatably mounted therein and are arranged one above the other, as illustrated. The rollers are provided with suitable spindles that are suitably journaled in the uprights 1 and 2. The roller 9 has a pulley 10 secured to one of its spindles by means of which roller 9 and all others are frictionally rotated. A pair of calendering roller pressure adjustment members 11 and 12 is disposed between roller 5 and top member 4 in order that the several rollers will be urged into engagement with each other and the stock worked on at a predetermined pressure.

The paper stock 13 is threaded about roll 5, then through the pass between rollers 5 and 6 and finally emerges from the last pass between rollers 8 and 9. The stock is kept in firm engagement with each roller between passes so that it will be threaded into the several passes without manual assistance. It is, however, threaded manually between guide mechanism 14 and roller 5 and it enters the first pass between rollers 5 and 6 without further assistance. The succeeding guide mechanisms 15, 16, and 17 are positioned opposite rollers 6, 7, and 8, respectively,

ly, as illustrated, to guide the stock 13 into the passes between the several rollers.

Each of the guide mechanisms comprises a pair of end frame members 18 and 19 and a back member 20 preferably integrally associated with the end members to connect and space them. The free or unsupported ends of members 18 and 19 are contoured generally to the shape of the calendering rollers 5—8. A plurality of rollers 21, 22, 23, etc., are rotatably arranged in the free ends of members 18 and 19 and are engageable with the calendering rollers. These rollers are spaced sufficiently close together so that stock 13 will be kept in engagement with the several calendering rollers. Rollers 21, 22, and 23 are relatively small in diameter and circumscribe substantially 180 degrees of the calendering roll surface.

Compression is maintained between the rollers of each guide mechanism and the associated calendering roller by means of a compression mechanism, one of which consists of a vertically disposed shaft 24 rotatably mounted in base 3 at its lower end and its upper end is rotatably supported in a suitable bracket 25 associated with uprights 1 and 2. Opposite each guide mechanism 15 and 17 disposed opposite calendering rollers 6 and 8, respectively, are back-up members 26 and 27 adjustably and resiliently supported on studs 28a threaded into the uprights 1 and 2. Springs 28 on the studs urge the back-up members outwardly against the nuts on the studs 28a. A plurality of cams 29 and 30, one for each back-up member, is mounted on shaft 24 and a handle 24' is secured to the shaft by means of which it is rotated. When shaft 24 is rotated to the position of Fig. 3, the guide mechanisms tightly engage the respective calendering rollers 6 and 8 and when rotated to the Fig. 4 position, they are disengaged therefrom.

The other guide mechanisms 14 and 16 disposed opposite calendering rollers 5 and 7 are moved by a shaft 30 whose upper end is rotatably supported in top member 4 and whose lower end is rotatably supported in a bracket 31 secured to uprights 1 and 2. The feed mechanisms have back-up members 32 and 33 adjustably supported on studs 34a threaded into uprights 1 and 2 and are urged outwardly by springs 34 against the nuts on studs 34a. A plurality of cams 35 and 36 is secured to shaft 30, one opposite each of the back-up members 32 and 33, and handle 30' secured to shaft 30 is employed to rotate the cams 35 and 36 to the two positions illustrated

in Fig. 3 for the same purpose as discussed in connection with guide devices 15 and 17.

An auxiliary member 37 in the form of a plate is resiliently supported on each guide member and whose lower end is pointed or knife edged is in engagement with the calendering roller disposed immediately above it so that the paper stock will be stripped from the calendering roller and guided between the roller 21 of the mechanism with which the guide 37 is associated. In the particular construction shown, the plate member 37 has at its inner end a depending flange 37^a adapted to bear against the outer side face of the upper marginal part of the back member 20 of the frame of the guide mechanism, said flange being provided with a small slot 37^b through which extends a bolt 39. The bolt 39 extends through an aperture in the back member 20 and has a nut 40 on the inner end portion thereof engaging the inner side face of the back member 20, a coiled expansion spring 41 being interposed between the head of the bolt 39 and the outer face of the flange 37^a so that the plate member 37 is supported for pivotal movement on the back plate 20 of the frame and is urged by said spring into engagement with the calender roll. Water trough 38 is positioned under each guide or feed member in the manner illustrated to collect water draining from the calendering rollers.

What I claim is:

1. In a calender rolling machine for paper stock having a plurality of rollers arranged in a row side by side providing a plurality of passes therebetween, a web guiding mechanism coacting with each of said calender rollers, the web guiding mechanism for adjacent rollers being disposed at opposite sides thereof, each web guiding mechanism including an elongated frame, a plurality of longitudinally extending guide rollers rotatably mounted in arcuate arrangement in said frame for engagement with the associated calender roller, the frame being supported for bodily movement laterally of the calender roller, means for urging the frame of the guide mechanism toward the calender roller for moving the guide rollers into engagement with the same, each web guiding mechanism excepting the one for the first of the series of calender rollers being provided with a longitudinally extending elongated plate member pivotally supported on the frame of said web guiding mechanism at one side of the same and having an edge portion engageable with the preceding calender roller, and a spring for yieldably urging said plate member into engagement with the calender roller.

2. In a calender rolling machine for paper stock having a plurality of rollers arranged in a row side by side providing a plurality of passes therebetween, a web guiding mechanism coacting with each of said calender rollers, the web guiding mechanism for adjacent rollers being disposed at opposite sides thereof, each web guiding mechanism including an elongated frame, a plurality of longitudinally extending guide rollers rotatably mounted in arcuate arrangement in said frame for engagement with the associated calender roller, the frame being supported for bodily movement laterally of the calender roller, a means for urging under spring tension the frame

of the guide mechanism toward the calender roller for moving the guide rollers into engagement with the same, each web guiding mechanism excepting the one for the first of the series of calender rollers being provided with a longitudinally extending elongated plate member pivotally supported on the frame of said guide mechanism at one side of the same and having an edge portion engageable with the preceding calender roller, and a spring for yieldably urging said plate member into engagement with the calender roller.

3. In a calender rolling machine for paper stock having a plurality of rollers arranged in a row side by side providing a plurality of passes therebetween, a web guiding mechanism coacting with each of said calender rollers, the web guiding mechanism for adjacent rollers being disposed at opposite sides thereof, each web guiding mechanism including a frame, a plurality of longitudinally extending guide rollers rotatably mounted in arcuate arrangement in said frame for engagement with the associated calender roller, the frame being supported for bodily movement laterally of the calender roller, means for bodily moving the frame of the guide mechanism laterally toward and from the calender roller to move the guide rollers into and out of engagement with the calender roller, each web guiding mechanism excepting the one for the first of the series of calender rollers being provided with a longitudinally extending elongated plate member pivotally supported on the frame of said guide mechanism at one side of the same and having an edge portion engageable with the preceding calender roller, and a spring for yieldably urging said plate member into engagement with the calender roller.

4. In a calender rolling machine for paper stock having a plurality of rollers arranged in a row side by side providing a plurality of passes therebetween, a web guiding mechanism coacting with each of said calender rollers, the web guiding mechanism for adjacent rollers being disposed at opposite sides thereof, each web guiding mechanism including an elongated frame, a plurality of longitudinally extending guide rollers rotatably mounted in arcuate arrangement in said frame for engagement with the associated calender roller, the frame being supported for bodily movement laterally of the calender roller, means for urging under spring tension the frame of the guide mechanism toward the calender roller for moving the guide rollers into engagement with the same, each web guiding mechanism excepting the one for the first of the series of calender rollers being provided with a doctor plate member supported on the frame of said guide mechanism at one side of the same and having an edge portion engageable with the preceding calender roller.
